UNITED STATES PATENT OFFICE.

ROBERT E. HUMPHREYS, OF WHITING, INDIANA, ASSIGNOR TO STANDARD OIL COMPANY, OF WHITING, INDIANA, AND CHICAGO, ILLINOIS, A CORPORATION OF INDIANA.

PRESSURE OIL STILL.

Application filed January 7, 1921. Serial No. 435,700.

To all whom it may concern:

Be it known that I, ROBERT E. HUMPHREYS, a citizen of the United States, residing at Whiting, in the county of Lake 5 and State of Indiana, have invented a new and useful Improvement in Pressure Oil Stills, of which the following is a specification.

The present invention relates to oil stills, 10 and more particularly to such stills intended for the distillation of oil under high pressure, for example, pressures of the order of 350 pounds per square inch. It will be fully understood from the following description 15 thereof, illustrated by the accompanying drawings, in which a specific embodiment of the invention is shown.

In the drawings:

Fig. 1 is a vertical section thru the still, 20 the setting being likewise shown in section;

Fig. 2 shows upon the left half of the figure a front elevation of the still, the front of the setting being shown in section as indicated on the line 2—2 in Fig. 1, and 25 the right half of which shows a vertical section thru the still on the line 2^a—2^a of Fig. 1, and

Fig. 3 shows a front elevation of the still.

Referring more particularly to the drawings, the numeral 10 indicates the still setting, the parts of which will be described in greater detail in connection with the various parts of the still. In the front portion of the setting 10, a fireplace 11 or other suitable 30 combustion chamber is provided, the combustion gases issuing therefrom being forced to travel upwardly around the arch 12 thru the main heating chamber 13 and issuing from the furnace thru the flue 14.

40 A plurality of drums or cylinders 15, 16, 17, and 18, which extend longitudinally of the furnace setting, are arranged thereabove and serve as containers for the bulk supply of oil undergoing distillation. These drums, 45 which may be lagged, if desired, are preferably arranged in pairs, the drums of each pair being vertically disposed one above the other, as illustrated in connection with the pairs of drums comprising 15 and 16, or that comprising drums 17 and 18. As the relative arrangement of each pair of drums is the same, that of only one pair of drums 15 and 16 will be described in detail.

The drums 15 and 16 are positioned with their axes substantially parallel to each other, and the rear ends of the drums are preferably elevated slightly above the forward ends. The drums 15 and 16 are spaced from each other, and retained in their proper relationship by the spacers or webs 19, 19 60 which are supported upon the lower drum 16, and upon which the upper drum 15 rests. On each side of the center line of the drums, a plurality of curved or bent pipes 20, 20 extend from the lower portion of the upper drum to the upper portion of the lower drum, these pipes or tube sections being rolled into the walls of the drums at each end. Each pair of drums is supported in swings 21, there being at least one near the 70 front and one near the rear. These swings are suspended from the cross beams 22, which are mounted upon the uprights 23, 23. The rear wall of the furnace setting 10 is extended upwardly as indicated at 24 75 to a point such that it is barely cleared by the lowermost of each pair of drums and thus serves as a support for the drums in case of failure of the swings from which 80 they are supported.

A vapor outlet 25 is provided near the rear end of each of the upper drums of the several pairs of drums, and each of these vapor outlets communicates with a vapor manifold 26. The manifold 26 is in turn 85 provided with an outlet 27, which may communicate with a suitable vapor line or run back (not shown) connected to a condenser and the manifold 26 is likewise provided with an upwardly directed pipe connection 90 28 to which is attached an adjustable pressure safety valve 29.

At their forward ends each of the lower drums 16, 18 is connected by means of a downwardly depending leg 30 with a transverse, horizontal drum 31, which may suitably be supported on the top of the furnace setting 10, as more fully hereinafter described. At their rear ends, each of the lower drums 16, 18 is provided with a depending leg or downcomer 32 by which it communicates with a lower horizontal transverse drum 33, secured in the lower portion of the furnace setting 10. A plurality of upwardly inclined tubes 35, 35 extend from 100 the lower drum 33 thru the main combustion

- or heating chamber 13 to the upper drum 31. The lower drum is provided with a feed pipe 36 and a discharge pipe 37, preferably arranged near the opposite ends of the 5 drum. Plugs, as indicated at 38, 38 may be screwed into openings in the upper transverse drum 31 and their removal permits inspection of its condition and of that of the tubes 35.
- 10 The upper transverse drum 31, in the construction illustrated, is cradled in a depression in the front portion of the roof of the furnace, preferably in a bed of granulated fire brick or similar refractory material, 15 which is retained in position by suitable sealing plates 39. The lower transverse drum 33 is supported in a refractory brick cradle 40 between the rear wall of the furnace setting 10 and the wall 41 of the flue 14.
- 20 It is protected from the heat of the combustion chamber 13 by the bed 42 of granulated fire brick or similar refractory material, which is held in position by suitable sealing plates 43.
- 25 As is readily apparent, the fireplace may be provided with suitable inspection openings 45, 45, wherever deemed desirable.
- In beginning the operation of the still, the charging stock, which may be, for example, a heavy hydrocarbon oil of the character of the fuel oil distillate from mid-continent crude having a specific gravity of 32 to 34° Baumé, is charged into the still thru the feed pipe 36 until the uppermost 30 longitudinal drums 15, 17 are partially filled. The transverse drums 31 and 33, the tubes 35, 35, the legs 30, 30, the down-comers 32, 32, the lower longitudinal drums 16, 18 and the connecting tubes 20, 20 are 35 then completely filled with the oil. Firing is then begun and the vapors are permitted to escape freely until any water present in the charging stock has been removed. The vapor outlet 27 from the manifold 26 is then 40 connected with a suitable refluxing and condensing system (not shown), the still is placed under pressure, either autogenous or from an extraneous source, and firing continued until the stock in the still is brought 45 to the required or desired temperature. The pressure maintained upon the still may be, for example, 250 pounds per square inch, the temperature of the stock being controlled 50 to produce the desired rate of conversion 55 thereof into light boiling products, for example, of the gasoline type in the manner described in the prior application of Humphreys, Rogers and Paulus, Serial No. 312, 60 398, filed July 21st, 1919. The bulk supply 65 of the oil undergoing distillation is distributed thru the plurality of longitudinal drums, 15, 16, 17, 18, each of which is of relatively small diameter as compared with the diameter of a single drum which would 70 be required to contain the entire bulk supply 75 of oil. By the arrangement of the upwardly inclined tubes 35, 35 within the combustion chamber of the furnace, and their connection with the lower transverse drum 33 and the upper transverse drum 31, each of 75 which is connected with the longitudinal drums forming the bulk supply containers, a rapid semicyclic circulation of the stock is maintained during the entire heating period. During the distillation, fresh stock 80 may be supplied thru the feed pipe 36, or if desired, it may be supplied thru the run back connected to the vapor outlet 27. When it is desired to conclude the distilling operation, the firing is stopped, the still and its contents permitted to cool sufficiently to permit the removal of the tar or residuum thru the discharge pipe 37, and the still 85 may then be cleaned.
- 90 Altho the present invention has been described in connection with the specific details of an embodiment thereof, it is not intended that these details shall be regarded as limitations upon the scope of the invention, except in so far as included in the accompanying claims.
- I claim:
1. In an oil still for operation under high pressure, a plurality of sets of cylindrical oil containers, each set comprising an upper and a lower container, vapor outlets from the tops of said upper containers, a transverse drum below the lower containers of the said sets and communicating with one end of each thereof, a second transverse drum below the first mentioned transverse drum and communicating with the other end of the lower containers of said sets of containers, upwardly directed tubes between said transverse drums, and means for applying heat to said tubes.
- 95 100 105
2. In an oil still for operation under high pressures, a plurality of pairs of cylindrical oil containers, the containers of each pair being arranged one vertically above the other, spacing means between the upper and lower container of each pair, a plurality of curved tubes connecting the upper and lower container of each pair and establishing free communication therebetween, a vapor outlet from the upper container of each pair, said vapor outlets being manifolded, heating means, and means for flowing a stream of oil from one of each pair of containers through the heating means and back to the pair of containers.
- 110 115 120
3. In an oil still for operation under high pressures, a plurality of pairs of parallel cylindrical oil containers, the containers of each pair being arranged one vertically above the other, spacing means between the upper and lower container of each pair, a plurality of curved tubes connecting the upper and lower container of each pair and establishing free communication therebe-
- 125 130 135

- tween, a vapor outlet from the upper container of each pair, said vapor outlets being manifolded, a cylindrical drum below the forward ends of the lower containers of the 5 pairs of containers, a conduit from the forward ends of each of said lower containers to the drum, a second cylindrical drum below the rear ends of the said lower containers and at a lower level than the first 10 mentioned drum, a conduit from the rear end of each of said lower containers to the second drum, a plurality of upwardly inclined tubes between the drums, and means for heating the tubes.
- 15 4. In an oil still, a pair of cylindrical oil containers arranged one vertically above the other, spacing means between the containers, tubes between the containers and establishing free communication therebetween, elevated supports, and depending swings suspended from said supports in which the containers are supported.
- 20 5. In an oil still, a pair of cylindrical oil containers arranged one vertically above the other, spacing means between the containers, tubes between the containers and establishing free communication therebetween, elevated supports, depending swings suspended from said supports in which the containers 25 are supported, a furnace setting below the containers, a wall of the setting being extended upwardly to slightly below the lowermost of the containers, heating means within the setting and means for conducting a 30 stream of oil from the containers through the setting and back to the containers.
- 35 6. In an oil still for operating under high pressures, a heating chamber, upper and lower transverse cylindrical drums exterior 40 of said chamber, means placing the interiors of said drums in communication and extending through the heating chamber, pairs of longitudinal containers above and exterior of said heating chamber, a conduit connecting one end of one of each of said pairs with the upper transverse drum and conduits connecting the other end of one of each of 45 said pairs with the lower transverse drum, said last named conduits being exterior of 50 said chamber.
- 55 7. An oil still for operation under high pressure comprising, in combination, a heating chamber, transverse oil drums above and below said chamber, means passing through the chamber affording free communication 60 between said drums, a plurality of sets of inclined vertically spaced cylindrical containers above said upper transverse drum, means establishing free communication between the containers of said sets, other means providing free communication between the lower end of the lowermost container of each set and the uppermost transverse drum, and other means exterior of said 65 chamber establishing free communication

between the upper end of the lowermost container of each of said sets, and the lowermost transverse drum.

8. In a still for cracking oil, a heating chamber having a furnace connected thereto, an upper and lower drum located outside said heating chamber and furnace, tubes connecting the drums and passing through the heating chamber, storage drums above and outside said heating chamber, and connections between said storage drums and said upper and lower drum, located outside said chamber.

9. In a still for cracking oil, a heating chamber having a furnace connected thereto, an upper and lower drum located outside said heating chamber and furnace, tubes connecting the drums and passing through the heating chamber, storage drums above and outside said heating chamber, and connections between said storage drums and said upper and lower drum, located outside said heating chamber, the combustion chamber of said furnace being constructed and arranged so that the tubes are protected from the direct radiant heat of the furnace.

10. In a still for cracking oil, a heating chamber having a furnace connected thereto, an upper and a lower transverse drum located outside said heating chamber and furnace and extending beyond both said walls thereof, tubes extending through said heating chamber and connecting the upper and lower drums, longitudinal drums located above said furnace, and connections between said longitudinal drums and said upper and lower drums, said connections being located entirely outside said heating chamber and said furnace.

11. In a still for cracking oil, a heating chamber having a furnace connected thereto, an upper and a lower transverse drum located outside said heating chamber and furnace and extending beyond both side walls thereof, tubes extending through said heating chamber and connecting the upper and lower drums, a pair of longitudinal drums each located above an end of said upper drum and connections between each end of said upper drum and one of said longitudinal drums.

12. In a still for cracking oil, a heating chamber having a furnace connected thereto, an upper and a lower transverse drum located outside said heating chamber and extending beyond both side walls thereof, tubes extending through said heating chamber and connecting the upper and lower drums, a pair of longitudinal drums each located above an end of said upper drum and connections between each end of said upper drum and one of said longitudinal drums and between each end of said lower drum and one of said longitudinal drums, said

- connections and said tubes being constructed and arranged so that the resistance to flow in said connections is not greater than the resistance to flow in said tubes.
- 5 13. In a still for cracking oil, a pair of horizontally extending storage drums arranged one above the other and connected by a series of nipples spaced along their length and arranged to permit a free circulation of the oil between the drums, the lower drum having an oil inlet at one end and an oil outlet at the opposite end constructed and arranged to produce a general circulation of oil through the drum and longitudinally thereof.
- 10 14. In a still for cracking oil, a pair of horizontally extending storage drums arranged one above the other and connected by a series of nipples spaced along their length and arranged to permit a free circulation of the oil between the drums, the lower drum having an oil inlet at one end and an oil outlet at the opposite end constructed and arranged to produce a general circulation of oil through the drum and longitudinally thereof, said nipples being curved to permit expansion without undue strain on the connections between the nipples and the drums.
- 15 15. In a still for cracking oil, a pair of horizontally extending storage drums arranged one above the other and connected by a series of nipples spaced along their length and arranged to permit a free circulation of the oil between the drums, the lower drum having an oil inlet at one end and an oil outlet at the opposite end constructed and arranged to produce a general circulation of oil through the drum and longitudinally thereof, at least the upper storage drum being inclined to provide a vapor and gas outlet near the highest end of the drum and the oil inlet and outlet of the lower drum being arranged to cause the general circulation of oil through the drums in a direction toward said vapor and gas outlet.
- 20 16. In a still, an upper and a lower transverse drum, heating tubes connecting the transverse drums, a longitudinal storage drum above the upper transverse drums, connections between the upper and the lower transverse drums and the longitudinal storage drum, and a furnace to heat the tubes, constructed and arranged so that all of the drums and their connections other than the heating tubes are protected from the heat of the furnace, said longitudinal storage drum being inclined to form a vapor space at one end thereof and a vapor outlet in said drum connecting with said space.
- 25 17. In a still for cracking oil, an upper and a lower transverse drum, heating tubes connecting the drums, longitudinal storage drums arranged one above the other in tiers above the upper transverse drum, a connection leading from the upper transverse drum to a point adjacent one end of the lowest drum of each tier of storage drums, and a connection leading downward from near the opposite end of the lowest drum of each tier of storage drums to the lower transverse drum, the longitudinal drums in each tier being connected by nipples spaced at intervals along the axes of the drums.
- 30 18. In a still for cracking oil, an upper and a lower transverse drum, heating tubes connecting the drums, longitudinal storage drums arranged one above the other in tiers above the upper transverse drum, a connection leading from the upper transverse drum to a point adjacent one end of the lowest drum of each tier of storage drums, and a connection leading downward from near the opposite end of the lowest drum of each tier of storage drums to the lower transverse drum, the longitudinal drums in each tier being connected by nipples spaced at intervals along the axes of the drums, said nipples being curved to permit expansion without undue strains.

ROBERT E. HUMPHREYS.
